CONVEYER STOP

James L. Eiselstein, Berkeley, Calif.

Application January 27, 1940, Serial No. 316,000

2 Claims. (Cl. 198—232)

This invention relates to improvements in stop motion devices for use with conveyers and the like moving belt arrangements.

The principal object of this invention is to provide means for automatically stopping the motion of a conveyer, belt, or the like when the conveyer breaks or otherwise becomes loose.

A further object of the invention is to produce a device of this character which is simple to construct and easy to install on any standard conveying apparatus without materially altering its construction.

A further object of the invention is to produce a device of this character which is compact and, therefore, one which requires but little room in which to operate.

Other objects and advantages will be apparent during the course of the following description.

In the accompanying drawing forming a part 20 of this specification and in which like numerals are employed to designate like parts throughout the same,

Fig. 1 is a side elevation of my device as the same would be applied adjacent the wheel of a 25 conveyer;

Fig. 2 is a top plan view of Fig. 1;

Fig. 3 is an enlarged cross sectional view taken on the line 3—3 of Fig. 1; and

Fig. 4 is an enlarged cross sectional view taken 30 on the line 4—4 of Fig. 1.

There are many industries wherein a conveyer or belt travels between two spaced pulleys for the purpose of transporting material on the upper surface thereof from a point adjacent one of the 35 pulleys to a point adjacent the other pulley. Sometimes these belts or conveyers are constructed of links travelling over sprockets instead of plain pulleys. Irrespective of the type of conveyer, considerable damage may occur should the 40 conveyer break; and when the conveyer does break, it often requires many hours of labor to reinstall and repair the same.

I have, therefore, devised an apparatus which 45 may be attached adjacent the conveyer and which will actuate a stop motion device as soon as the conveyer breaks and a portion thereof comes into engagement with my device.

In the accompanying drawing wherein for the 50 purpose of illustration is shown a preferred embodiment of my invention, the numeral 5 designates a support upon which a bearing 6 is mounted. This bearing serves to support one of the spaced conveyer pulleys or sprockets, designated by the numeral 7, and over which the con-

veyer 8 passes. The construction thus far described is standard equipment.

My device consists of an arm 9 extending beneath the conveyer and being formed integral with a crank arm 11 pivoted in bearings 12 beneath the support 5. An upwardly extending lever 13 has its end 14 in engagement with a push rod 16 slidably mounted on the support 5. This push rod has a return bend 17 which has its free end 18 extending through guide plates 19 supported on a bracket 21 mounted on the support 5. A slider 22 is mounted between the guide plates 19 and has a nose 23 in alignment with a push button 24 electrically connected to a circuit breaker (not shown). Pivoted as at 26 is 15 a lever 27, to the free end of which is connected a weight 28. An arm 29, also connected to the lever 27, bears against the back of the slider 22.

The result of this construction is that when the parts are in the position shown in full lines 20 in Fig. 1, the conveyer may operate in the usual manner. Should the conveyer break, the same will drop against the arm 9, causing the crank arm 11 to transmit motion through the lever 13 to the end 14, contacting the push rod 16, which 25 will move the parts to the dotted line position of Fig. 1. As this occurs, the end 18 will be moved out of contact with the nose 23 of the slider 22 and also out of the path of movement of the slider. Therefore, the pivoted lever 27 will drop, 30 because of the weight attached thereto, to the dotted line position of Fig. 3, causing the arm 29 to push the slider toward the right of the figure, bringing the nose 23 into engagement with the electrical button 24 which, when worked, will 35 serve to operate a circuit breaker to cut off power from driving the conveyer further.

It will thus be seen that I have produced a device which is extremely simple in construction and one which may be readily applied as above 40 set forth.

It is to be understood that the form of my invention herewith shown and described is to be taken as a preferred example of the same and that various changes relative to the material, 45 size, shape and arrangement of parts may be resorted to without departing from the spirit of the invention or the scope of the subjoined claims.

Having thus described my invention, I claim: 50

1. In combination with an endless conveyer, of a lever pivoted adjacent thereto and extending therebeneath, a push rod in alignment with one end of said pivoted lever and capable of endwise movement, said rod having a return bend at the 55

opposite end thereof from said alignment with said lever, a slider normally engaging the free end of said return bend, and means for moving said slider when said free end is moved out of engagement with said slider through the actuation of said pivoted lever.

2. In combination with an endless conveyer, of a lever pivoted adjacent thereto and extending therebeneath, a push rod in alignment with one end of said pivoted lever and capable of end-
wise movement, said rod having a return bend

at the opposite end thereof from said alignment with said lever, a slider normally engaging the free end of said return bend, means for moving said slider when said free end is moved out of engagement with said slider through the actuation of said pivoted lever, said means for moving said slider including a pivoted lever, a weight connected to said pivoted lever, and an arm bearing against said slider to transmit movement thereto.
